UNITED STATES PATENT OFFICE.

FRANK E. BUDDINGTON, OF CHICAGO, ILLINOIS.

LIQUID-EVAPORATOR FOR HEATERS.

1,090,835.

Specification of Letters Patent. Patented Mar. 24, 1914.

Application filed April 3, 1913. Serial No. 758,738.

all who it may concern:

Be it known that I, FRANK E. BUDDINGTON, a citizen of the United States, residing at Chicago, county of Cook, and State of Illinois, have invented certain new and useful Improvements in Liquid-Evaporators for Heaters, of which I do declare the following to be a full, clear, and exact description.

10 The present invention has for its object to provide an improved construction of liquid evaporator adapted to be used in connection with radiators, hot air registers or like apparatus, whereby the heating of the 15 air of rooms or the like is effected, the purpose of the invention being to impart to the heated air a desired degree of moisture.

The invention consists in the features of novelty hereinafter described, illustrated 20 in the accompanying drawing and particularly pointed out in the claims at the end of this specification.

Figure 1 is a view in side elevation of the upper portion of the radiator of a hot 25 water system, my improved liquid evaporator being shown on top thereof and in vertical section on line 1--1 of Fig. 2. Fig. 2 is a plan view of my improved liquid evaporator, a portion only of the fabric being 30 shown. Fig. 3 is a view in cross-section on line 3--3 of Fig. 2. Fig. 4 is a plan view of a radiator showing a modified form of my invention applied thereto. Fig. 5 is a view in vertical cross-section of the modified form of evaporator shown in Fig. 4, a part of the radiator being indicated by dotted lines in side elevation.

While for illustration I have shown my invention as applied in connection with a hot 40 water radiator, it will be readily understood that it can be used in connection with hot air registers or in other situations in which it is desired to impart moisture to the air of a room.

45 In the accompanying drawing, 10 designates a hot water radiator of familiar construction.

My improved liquid evaporator comprises a pan or receptacle 11 for holding a supply 50 of water. To afford a firm support for the receptacle 11, it is preferably attached to an open-work base 12. This base 12 is shown as consisting of a border frame 13 and between the sides and ends of which extend 55 the wires 14. Inasmuch as the parts of the base 12 which project beyond the receptacle

11 are thus open or reticulated, the hot air can ascend freely through the base.

From the top of the receptacle or pan 11 projects an open-work fabric support 15 60 adapted to sustain a sheet or strip of fabric 16. This fabric 16 is preferably of thin open material of lace-like texture, so as to permit the passage therethrough of the heated air, and a portion of this fabric will dip 65 into the liquid within the receptacle 11, and this liquid, by capillary attraction, will be drawn up from the pan and will be distributed over the surface of that portion of the fabric 16 that rests upon the fabric sup- 70 port. In the preferred form of the invention, the fabric support 15 is shown as extending at opposite sides of the liquid receptacle 11 at the upper part thereof, and preferably this fabric support is contained 75 within a frame or hood 18 that is securely fastened to the top portion of the liquid receptacle 11. As shown, the frame or hood 18 extends not only a slight distance above the level of the fabric support 16, but also 80 to a distance below the same, the purpose of the depending portion of the hood being to better insure the upper passage of the heated air through the fabric support and fabric.

85 From the foregoing description it will be seen that when the sheet of fabric 16 is placed within the liquid in the receptacle 11, and the portion or portions of the fabric are wet and distended over the fabric sup- 90 port 15, the water from the receptacle 11 will be drawn up by capillary attraction and distributed over the distended portions of the fabric 16 so that as the heated air rises through the fabric support and fabric, 95 it will gradually evaporate the water carried by the fibers of the fabric and thus moisten the heated air. If desired, the fabric support may be furnished with suitable fastening devices, weights or the like for 100 holding the fabric in position upon the surface of the fabric support.

In the form of the invention illustrated in Figs. 4 and 5 of the drawing, I have shown a round receptacle or water pan 11^a. 105 To the bottom of this pan is secured an open-work base 12^a and from the top of which is secured an annular open-work fabric support 15^a. This annular open-work fabric support 15^a is surrounded by a hood 110 or frame 18^a that corresponds with and performs the same function as the hood or

frame 18 in the form of the invention hereinbefore described.

It will be understood that the precise details of construction above set out may be varied without departing from the spirit of the invention, and that features of the invention may be employed without its adoption as an entirety.

Having thus described my invention what 10 I claim as new and desire to secure by Letters Patent, is:—

1. A liquid evaporator comprising the combination of a liquid receptacle, an open-work fabric support secured to said receptacle adjacent its top and extending laterally therefrom, and a hood around the edges of said openwork fabric support and depending therefrom.

2. A liquid evaporator comprising the combination of a pan-shaped liquid receptacle having an open top as broad as the body of said receptacle, an open work fabric support secured to said receptacle adjacent its top and extending laterally therefrom at opposite sides thereof, and a thin open material of lace-like texture to admit the passage of air therethrough resting upon said fabric support and extending into said receptacle.

30 3. A liquid evaporator comprising the

combination of a pan-shaped liquid receptacle having a broad open top, an openwork fabric support secured to said receptacle adjacent its top and extending laterally therefrom on opposite sides thereof, a hood extending around the outer edge of said openwork fabric support and above and below the same, and a fabric of thin open material extending over said openwork support and into said pan-shaped receptacle.

4. A liquid evaporator comprising the combination of a pan-shaped liquid receptacle having a broad open top of substantially the same area as the body of the receptacle and having a flat bottom, a laterally projecting openwork base at the bottom of said receptacle and extending outwardly therefrom at opposite sides thereof, an open-work fabric support secured to said receptacle adjacent its open top and extending laterally therefrom, a hood extending around the outer edges of said openwork fabric support, and a sheet of thin fabric extending into said vessel and over said openwork fabric support.

FRANK E. BUDDINGTON.
